Des. 240,599
Patented July 20, 1976

240,599

MOLDED WALL FASTENER

Alan J. Solo, Brooklyn, N.Y., assignor to Knock-N-Lok International, Inc., Brooklyn, N.Y.

Filed Jan. 8, 1975, Ser. No. 539,275

Term of patent 14 years

Int. Cl. D8—08

U.S. Cl. D8—271

FIG. 1 is a perspective view of a molded wall fastener showing my new design;

FIG. 2 is a top plan view;

FIG. 3 is a side elevational view;

FIG. 4 is a bottom plan view; and

FIG. 5 is a rear elevational view.

I claim:

The ornamental design for a molded wall fastener, substantially as shown.
